UNITED STATES PATENT OFFICE.

CHARLES E. CONNER, OF AUBURN, MAINE, ASSIGNOR TO UNITED SHOE MACHINERY CORPORATION, OF PATERSON, NEW JERSEY, A CORPORATION OF NEW JERSEY.

METHOD OF MAKING SHOES.

1,382,763.

Specification of Letters Patent. Patented June 28, 1921.

Original application filed September 10, 1918, Serial No. 253,411. Divided and this application filed December 8, 1919. Serial No. 343,365.

To all whom it may concern:

Be it known that I, CHARLES E. CONNER, a citizen of the United States, residing at Auburn, in the county of Androscoggin and 5 State of Maine, have invented certain Improvements in Methods of Making Shoes, of which the following description, in connection with the accompanying drawings, is a specification, like reference characters on the 10 drawings indicating like parts in the several figures.

The present invention relates to improvements in methods of assembling shoe parts and more especially to improved methods of 15 making shoes of the type known as "turn" shoes. For purposes of illustration the invention is herein set forth with particular reference to its utility in incorporating counters, such as previously molded counters, 20 in turn shoes made in accordance with the method disclosed in United States Patent to J. K. Thissell No. 1,302,994.

According to the Thissell method of incorporating a molded counter in a turn shoe, 25 the molded counter is attached to the heel portion of the sole after the shoe upper has been secured to the sole inside out in the well-known manner of making turn shoes but prior to turning the shoe right side out. 30 It is of especial importance in practising this method properly to locate the counter in an upright or final position relatively to the sole with particular reference to the interior dimensions of the shoe after the shoe is 35 turned to obtain a shoe of the desired predetermined size and to insure the second last fitting the shoe snugly. Moreover, it is essential that the counter should be permanently and strongly attached in the position 40 it is finally to occupy in the finished shoe in spite of any handling which would be liable to displace the counter. A further difficulty arises from the heel seat nailing operation which has heretofore been performed after 45 the shoe is turned since the heel seat nails unless carefully inserted are liable to interfere with subsequent heel attaching and finishing operations on the shoe and also the heel seat nailing operation necessitates an 50 additional handling of the shoe.

The invention has for an object to provide an improved method of assembling molded counters and turn shoe parts to the end that the counters may be incorporated in the shoe

efficiently and economically and in such 55 manner that they will be permanently in the correct relation to other shoe parts and especially in correct widthwise relation in the shoe.

The practice of the invention is a preferred manner comprises first securing a shoe upper inside out to a sole in the customary manner of making turn shoes, then placing the said shoe upon a shoe support, placing a molded counter upon a counter 60 support and effecting relative movement between the said shoe and the said counter to assemble the counter upon the sole in the position it is to occupy relatively to the sole when the shoe is turned inside out and thereafter finally attaching the counter to the 65 shoe in said position.

In another of its aspects the invention 70 contemplates securing the counter in its finally assembled position in the shoe prior to turning the shoe right side out by the insertion of a plurality of fastenings so located as to attach the inturned flange of the counter to an underlying portion of the 75 sole.

A machine which may be used for carrying out the method of the present invention 80 constitutes the subject-matter of my co-pending application Serial No. 253,411, filed September 10, 1918, of which this application is a division.

Other objects and features of the invention will appear from the following description when considered in connection with the accompanying drawings which illustrate a 90 preferred procedure of the method and the invention will then be pointed out in the appended claims.

In the drawings,—

Figure 1 is a view in side elevation of 95 a fastening inserting machine by the use of which the method may be practised, parts of the construction being shown in section and other parts being broken away for clearness of illustration;

Fig. 2 is a view in side elevation and partly in section illustrating the relative location of the shoe and the operating elements of the machine prior to the insertion of the fastenings to attach the counter to 105 the shoe;

Fig. 3 is a perspective view of a shoe after being operated upon by this machine.

The drawings illustrate a preferred form of counter attaching machine which may conveniently be used in the practice of the method of the invention. This machine, as 5 illustrated, comprises a frame provided with a stationary cross bar 4 in which are formed a plurality of driver passages 6 through which reciprocate the drivers 8 carried by the cross head 10. The cross head is secured to the upper ends of side rods 12 which reciprocate in vertical journals formed in the frame 2. The reciprocation of the cross head 10 may be effected in any suitable manner, for example, through a 15 lower cross head connected with an eccentric on the driving shaft of the machine as shown in the patent to Pope No. 446,885, granted Feb. 24, 1891. In the lower part of the frame vertical guideways are provided for a jack carriage support and a 20 superimposed jack carriage 16. The latter is provided with horizontal ways 17 for the jack 18 which carries the shoe to be operated upon, the jack comprising a vertically 25 adjustable heel post 19 carrying a last pin 20 and an adjustable toe post 21 to support the toe of the shoe. The jack carrier 16 is elevated to bring the heel seat portion of the shoe in work clamping relation to the 30 nail inserting mechanism by suitable power operated mechanism in the base of the machine. As shown in the patent to Pope above referred to, a nail loader is provided to furnish the nail block with the required 35 number of nails to be driven, these nails being preferably of the headed type to insure the holding effect of the nails.

Centrally mounted on the under surface 40 of the stationary cross bar 4 by means of the bolt 24 and dowel pins 26 is a block 28 which serves to support a shoe counter 30 for attachment in upright position on the heel seat of the shoe 32. This block 28 is shaped to enter the smallest size of counter 45 to be used so that it will not be found necessary to substitute various sizes of counter supporting blocks when operating upon different sizes of shoes and it has its bottom surface slightly concaved to correspond to the convaxed heel seat surface of the shoe, thus insuring a proper seating and clamping 50 of the inturned flange of the counter on the heel seat. Driver guiding passages 6 are also formed in this counter block in continuation of the driver passages 6 in 55 the cross bar 4. On opposite sides of the counter block 28 and near its forward edges are a pair of spring clips 36 extending downwardly and rearwardly to a point near 60 the lower edge of the block for retaining the counters on the block. These clips, which are conveniently narrow strips of spring steel, depend from ears 38 carried by a left and right threaded screw 40 extending transversely through the block and

they have their outer ends curved slightly inwardly so as to grip the counter and cause it better to hug the counter block. The screw 40 which has thumb holds at either end provides for simultaneous lateral adjustment 70 of the clips 36 to accommodate different sizes of counters on the block, a set screw 44 being provided to lock the screw in any of its adjusted positions. Extending downwardly from the under side of the cross bar 75 4 to which it is secured by the screw 48 and against the rear surface of the block 28 is another spring clip 50 which co-operates with the clips 36 correctly to position the counter on the counter supporting block and hold it against displacement. The driver guiding passages 6 in the cross bar 4 and in the counter block 28 are located as near as practical to the outer wall of the block 28 in a U-shaped design to insure the nails being driven through the inturned flange of the counter and adjacent to its inner wall. Also, the drivers 8 and driver passages 6 are so arranged that they do not insert fastenings forwardly of substantially the heel 80 breast line of the shoe to be operated upon; otherwise, in turn shoes, the clenched ends of the nails would appear on the finished surface of the sole.

The shoe and the counter are accurately 95 positioned relatively to each other by means of a shoe engaging gage 52 and a counter engaging gage 54 both of which are mounted for vertical adjustment and for a limited yielding movement so that they will accompany the shoe in its slight downward displacement when subject to pressure. For this purpose a rod 56, the upper end of which carries the gages 52, 54, is slidingly mounted at its lower end in a bracket 58 100 and is normally maintained in an elevated position by a compression spring 60 which encircles the end of the rod as shown in Fig. 1. Near its upper end the rod 56 slides in an angle piece 62 having a threaded shank 105 63 which extends through the forks of a bracket 64 on the machine frame. An adjusting nut 65 on the shank 63 serves to determine the adjusted position of the shoe or sole gage and, therefore, the position of the 110 shoe longitudinally of the counter. This gage is of considerable importance in the use of the machine and in the performance of the steps attendant upon the attachment of the counter to the shoe, since the location 115 of the shoe relatively to the counter when attached predetermines the interior dimensions or final size of the shoe, and unless accuracy in relatively locating the shoe and counter is insured subsequent operations on 120 the shoe are impaired and a shoe of the wrong size is produced. The counter gage 54 is located immediately above the sole gage 52 and is mounted for adjustment relatively to the sole gage and in the direction 125 130

but independently of the sole gage adjustment by means of a set nut 66 on the end of the rod 56, which projects through a slot in the counter gage. The forward end or 5 counter engaging surface of the gage 54 is inclined backwardly as shown in Fig. 2 so as to force the vertical inner wall of the counter, particularly at its junction with the inturned flange portion, against the lower 10 edge of the counter supporting block.

In the use of the invention with the machine herein illustrated, the shoe upper is first attached to the sole while inside out as described in the above mentioned patent 15 to Thissell. The jack 18 is next pulled outwardly in the ways 17 of the jack carriage and the shoe 32 on the last is placed on the heel post 19 with its toe resting on the toe post 21, the jack being then adjusted for 20 height and for the length of the shoe in question. The jack and the shoe are then pushed rearwardly into the machine until the rear end of the sole of the shoe engages the sole gage 52 which is then adjusted by 25 means of the adjusting screw 65 to locate the heel seat of the shoe in predetermined longitudinal relation to the counter 30.

In the next step of the process the previously molded counter of the proper size 30 and shape to fit the shoe which is being made is placed over the counter supporting block 28, the side walls of the counter being sprung under the side clips 36 which, by reason of their inwardly curved lower ends 35 engage the counter near its lower edge and hold it in position on the block. When counters are being used which are not held in some way in final position against spreading; for example, a half molded counter, 40 the side clips also serve to maintain the counter in the desired shape on the block, the spread of the counter being predetermined by the lateral adjustment of the clips through the adjusting nuts 42. The rear 45 upper edge of the counter is also definitely located on the block by the clip 50 and to insure the firm seating of the counter with its inturned flange overlaying the bottom of the block and its inner wall in contact with 50 the wall of the block, the inclined surface of the counter gage 54 is forced against the lower edge of the counter as shown in Fig. 2. Thus the counter is firmly supported in 55 predetermined position relatively to the shoe and the inturned flange of the counter is in position on the bottom of the block to receive the nails inserted through the driver passages 6. It will be obvious to those skilled in the art that with the Thissell practice of incorporating molded counters in turn shoes the accurate location of the counter upon the heel seat of the sole is of especial importance since it determines the 60 interior dimensions of the shoe after it is turned right side out and therefore the final 65

size of the shoe. By providing mechanical means for supporting the counter of the shoe in a predetermined position and for supporting the shoe in assembled relation to the counter, including provision for effecting a fine adjustment of the shoe in the direction of its length, as in the illustrated machine, the two shoe parts may be permanently associated with absolute accuracy and 70 uniformity.

After the shoe and the counter have been properly positioned the machine is started and the jack 18 is elevated in direct vertical alinement with the counter supporting block 28 whereupon the counter is seated upon the heel seat of the shoe with increased and positive pressure. During this relative movement of the shoe and the counter the gages 50 and 52 are carried with them, thus preventing their displacement and then as the 85 shoe and counter settle under the pressure, the gages yield. While the shoe is thus held under pressure the attaching nails which are preferably headed are deposited by the loader in the driver passages 6 and driven 90 by the drivers 8. As previously explained the driver passages are located near the outer wall of the counter supporting block and consequently they pass through the in-turned flange of the counter and the margin 95 of the sole of the shoe being clenched upon the usual iron bottom provided on the last. The jack is then lowered, which removes the counter from its support, and pulled forward so that the shoe may be removed. 100

Having thus described my invention, what I claim as new and desire to secure by Letters Patent of the United States is:

1. The method of manufacturing turned shoes, which comprises rigidly supporting 105 a molded counter, pressing against the bottom of the counter thus supported, a sole to which an upper has been attached, fastening the counter to the sole and thereafter completing the manufacture of the shoe.

2. The method of manufacturing a turned shoe, which comprises rigidly supporting a molded counter by engagement with the inside thereof, pressing against the bottom 115 of the counter a sole to which an upper has been attached, fastening the counter to the sole and thereafter completing the manufacture of the shoe.

3. The method of manufacturing turned shoes, which comprises rigidly supporting 120 a molded counter, pressing against the bottom of the counter thus supported the upper face of the heel end of a sole to which an upper has been attached wrong side out, fastening the counter to the sole, turning 125 the shoe right side out, and thereafter completing its manufacture.

4. The method of manufacturing turned shoes, which comprises supporting a molded counter, clamping against the flange of the 130

counter a sole to which an upper has been attached wrong side out, fastening the counter to the sole while the parts are held clamped, and thereafter turning the shoe right side out and completing its manufacture.

5. The method of manufacturing turned shoes, which comprises rigidly supporting a sole and its attached upper, rigidly supporting a molded counter, effecting relative

movement of the two parts thus supported to bring the counter into proper assembled relation with respect to the sole and upper, permanently fastening the counter to the sole and thereafter completing the manufacture of the shoe.
